UNITED STATES PATENT OFFICE.

PAUL SIPTROTT, OF NEW YORK, N. Y.

DESIGN FOR A LAMP.

Application filed November 1, 1924. Serial No. 11,247. Term of patent 3½ years.

To all whom it may concern:

Be it known that I, PAUL SIPTROTT, a citizen of Germany, and a resident of the city of New York, borough of Manhattan, in the county and State of New York, have invented a new, original, and ornamental Design for a Lamp, of which the following is a specification, reference being had to the accompanying drawing, forming a part thereof, in which—

Figure 1 is a view in front elevation of my new design for lamp;

Figure 2 is a side view thereof.

I claim:

The ornamental design for a lamp as shown.

PAUL SIPTROTT.
